UNITED STATES PATENT OFFICE.

FREDERICK W. BERNAU, OF HILLSIDE, NEW JERSEY, ASSIGNOR TO ELLIS ADDING-TYPEWRITER COMPANY, OF NEWARK, NEW JERSEY, A CORPORATION OF NEW JERSEY.

ELECTRIC DRIVE FOR CALCULATING MACHINES.

Application filed January 19, 1924. Serial No. 687,395.

This invention relates to those motor driven mechanisms, commonly known as "electric drives," for operating calculating machines to put such machines through their cycle of operation when a starting bar or key is manipulated.

My invention is an improvement on electric drives of the modern type which employ a constantly running electric motor for rotating a worm pinion and worm gear, combined with a clutch which is controlled by the starting bar or key to become effective when said key or starting bar is manipulated.

Modern practice requires that drives of the character set forth will, after the clutch has become engaged, cause the calculating machine to go through its cycle of operations, and then to automatically throw out or release the clutch, unless the starting bar or key is held in its operative position. Electric drives for the purpose set forth are subject to sudden shock when the clutch is engaged, this shock being communicated to the mechanism of the calculating machine.

I therefore provide means, in the nature of a yielding drive or coupling, interposed between the worm pinion and the motor shaft to absorb the shock when the clutch is thrown in and to thus start the mechanism of the calculating machine without sudden jar.

The yielding drive or coupling for the worm pinion will, under usual conditions, hold sufficiently to transmit the driving action of the motor to the mechanism of the calculating machine but if, for any reason, the mechanism of the calculating machine has become locked or offers more than the usual resistance, the yielding drive or coupling will permit slippage so that, while the motor will continue to operate, no damage will be done to either the driving mechanism or the operating mechanism of the calculating machine.

Electric drives for operating calculating machines must be positive in their clutching and de-clutching actions, have no "over-throw", possess extreme durability, and be simple and invariably accurate, as well as adapted to clutch and de-clutch quickly and without possibility of failure.

My electric drive embodies improvements and novel combinations of elements by which the mechanism fulfills all of the foregoing requirements. The worm gear is provided with a plurality of engageable devices, which may be holes, and constitutes the continuously driven member of the clutch. The other member of the clutch is a normally stationary, rotarily mounted, plate or disk which carries a driving pin positioned to engage the nearest engageable device, or hole, of the worm gear. The driving pin is adapted to establish the engagement aforesaid when it is released but is normally restrained by a restoring latch cooperating with an improved operating lever combined with the starting bar of the calculating machine.

When the starting bar is depressed, the restoring latch is freed and, thereupon, spring means snaps the driving pin into the nearest hole of the worm gear, thus coupling the driving plate to the worm gear so that it rotates with the latter for one complete revolution whereupon it is automatically retracted by the re-engagement of the restoring latch with the operating lever unless the starting bar is held down; in the latter event the driving plate continues to rotate with the worm gear as long as the starting bar remains depressed.

The operating means of the calculating machine has an operative connection to the driving plate and said operating means of the calculating machine will be actuated once, or as many times as desired, according to the manipulation of the starting bar.

An improved device, in the nature of a back stop pawl, provides means which prevents "lash" or swinging movement of the driving plate and holds it positively against back kick when the driving plate is arrested.

The invention also embraces other improved features and novel combinations of parts appearing more fully from the following description of the practical embodiment of the invention which is shown in the accompanying drawings.

I am aware that changes may be resorted to in carrying out the essential principles of the invention which is not intended to be

limited to the details of construction hereinafter described except where specified in the claims.

In the accompanying drawings:

5 Figure 1 is a side elevation showing the electric drive combined with an "Ellis" calculating machine, certain parts being in section and a part of the casing being omitted.

10 Fig. 2 is a vertical section on the line 2—2, Fig. 1, certain parts being in full lines.

15 Fig. 3 is a detail vertical section through the lower part of the casing, a lubricant reservoir, worm and worm gear on the line 3—3, Fig. 2.

15 Fig. 4 is a detail view of the restoring latch.

Fig. 5 is a plan view thereof.

19 Figs. 6 and 7 are front and side views of the driving collar.

20 Fig. 8 is a plan view of the operating lever.

Fig. 9 is a front elevation thereof.

25 Fig. 10 is a front view of the spring which actuates the driving pin.

25 Fig. 11 is a plan view of the back stop pawl.

Fig. 12 is a front view thereof; and

Fig. 13 is an end elevation thereof.

30 While the present invention is shown and described as combined with a calculating machine, it is to be understood that it is not restricted to this use, nor to use with an "Ellis" calculating machine, as my electric drive may be employed as a clutch in connection with other machines and for other purposes where an effective positive clutch action with an automatic throwout or de-clutching arrangement of simple form and great durability is required without the use 35 of an oil bath for the parts to run in.

35 In Figure 1 there is illustrated so much of the starting bar and operating mechanism of the "Ellis" machine disclosed in 40 patents and applications as will afford a clear understanding of the manner in which the present electric drive may be applied to said machine for the purpose of operating it.

45 The base of the machine is shown at 1. The Ellis machine has a shaft 2 to which 50 is fastened a drive plate 3. The electric drive, hereinafter described, is utilized to operate the calculating machine by links 4 whose construction and connections will be set forth hereinafter.

55 The starting bar of the machine appears at 5, said bar being supported by links 6 and 7, the former being pivoted at 8 to a three-armed piece 9 which is pivoted to the frame of the machine at 10. A ring shaped piece 11 which is pivoted to the frame of the machine at 12 is pivoted at 13 to the link 7 and, also to the piece 9.

60 By depressing the starting bar 5 the ring shaped piece 11 is turned in a counter-clock-

wise direction and the pin 15 of the three- 65 armed piece 9 is moved in a clockwise direction.

A lever 16 which has a slot receiving the pin 15 and which is pivoted at 17, constitutes the means by which the clutch herein- 70 after described is controlled. When the starting bar 5 is in its raised position, the lever 16 is so disposed that the clutch is thrown out but when the starting bar 5 is 75 depressed, the clutch is engaged.

The clutch mechanism and parts allied thereto are contained within a casing 18 which is securely, though detachably, fastened to the base 1 by screws 19. This casing has a flanged surface or face at its right 80 side, Fig. 1, which serves as an end shield for the motor 20 when the latter is attached to the casing by the screws 21.

The gear casing 18 is provided with a suitable bearing 22, Fig. 3, for the armature shaft 23 of the electric motor 20, the other bearing for the armature shaft being located at 24. Suitable lubricant containers or grease cups 25 are provided for the bearings 90 aforesaid.

Fibre washers 26 are provided on the armature shaft to take whatever end thrust occurs between the shoulder on the armature shaft and the bearing 22.

95 Sleeved on the armature shaft 23, but not mechanically connected thereto, is a worm pinion 27 which is driven from the armature shaft, with adaptability to slip slightly to prevent, or absorb, the shock transmitted to the drive piece 3 incident to the sudden 100 clutching action which occurs when the clutch is thrown in and thus to prevent undue shock being transmitted to the mechanism of the calculating machine. The operating connection for the worm pinion 27 105 also permits slippage as between the worm pinion and the armature shaft 23 in the event that the calculating machine, or certain units thereof, become accidentally "stalled" or locked. The connection now to 110 be described serves as a safety device for the foregoing purposes.

Referring to Fig. 3, a driving pin 28 is securely fastened to the armature shaft 23 and is received in the slots 29 of a stop collar 30 which is sleeved on the armature shaft 23 (Figs. 3, 6, 7). A friction washer 31 of any suitable material is interposed between the stop collar 30 and the end of the worm 27. This construction provides a friction drive for the worm 27 at the right hand end thereof. At the left hand end of the worm, Fig. 3, there is located another friction washer 31 against which bears a steel washer 32. The armature shaft is provided with a screw threaded end on which is a castellated jamb nut 33 which is locked in its adjusted position by a cotter pin 34.

Interposed between the nut and the steel washer is a coil spring 35.

The tension of the spring 35 reacting against nut 33 and through the washers, 5 worm, and stop collar holds the driving pin 28 engaged with the notches 29 and affords the requisite frictional gripping action by which the worm 27 is driven from the shaft 23 through the washers 31.

10 Under ordinary conditions the foregoing frictional drive for the worm is sufficient to transmit the motion of the armature shaft 23 through the worm 27 to the clutch, hereinafter described, and to overcome the 15 resistance of the calculating machine so that the latter will be put through its cycle of operations when the starting bar 5 is depressed. The frictional drive thus provided is not of sufficient strength, however, 20 to drive the worm 27 if the calculating machine has, for any reason, become accidentally locked. In that event, the motor will continue to operate and the armature shaft 23 to revolve but the worm 27 will 25 remain stationary, that is, there will be a "slip" between the friction washers 31 and the worm. Similarly, when the starting bar 5 is depressed, there will be such momentary slippage in the friction drive by 30 the washers 31 as will absorb the sudden shock due to throwing in of the clutch and thus no appreciable shock will be transmitted to the calculating machine which will be started in its cycle of operations 35 quickly, though easily.

The invention is not limited to the specific safety device previously described as it may be found desirable to safeguard the motor and different mechanisms of the calculating machine by the employment of other safety devices.

40 A grease pan or container 36 is fastened to the bottom of the casing 18 by a screw 37 and is located directly under the worm 45 27 so that the worm 27 is supplied with lubricant. A cap 38, which is secured by screws 39 to the casing 18, covers the opening through which access is had to the nut 33, when adjustments are needed.

50 A stud or stub shaft 40 (Fig. 2) which is secured to the casing 18 by screw 41, constitutes the support for the revoluble worm wheel 42 which meshes with worm 27, and for the revoluble driving plate 43, said 55 wheel and driving plate constituting members of the clutch.

The stud 40 has parts 44 and 45 of different diameters, part 45 being smaller than part 44. The worm wheel 42 is mounted 60 on suitable anti-friction bearings 46. Similar anti-friction bearings afford a mounting for the driving plate 43.

The worm gear or wheel is provided with a series of engaging devices or holes 44 65 which are located the same distance from

the center of the stud 40 and are spaced apart at regular intervals.

The driving plate 43 is provided with a single hole 45 in which is adapted to slide the driving plunger or pin 46. The hole 70 45 is so located that the pin 46 may register with any one of the holes 44, the purpose being to provide for entry of the pin in the nearest hole when said pin is released and the revolution of the gear 42 brings one of 75 said holes opposite said pin.

The worm gear 42, driving plate 43 and pin or plunger 46 constitute a releasable clutch by which motion may be communicated from pinion 27 to the driving piece 3 80 of the calculating machine when the starting bar 5 is depressed to permit the pin 46 to enter one of the holes 44 in the continuously rotating wheel 42 in a manner which will appear hereinafter.

85 The driving pin 46 has a peripheral groove in its outer end which is embraced by the hooked part 47 of a restoring latch 48 (Fig. 4), whose lower end has a hole 49, through which passes a headed stud 50 90 having a screw threaded end screwed into a hole in the driving plate 43 (Fig. 2), the connection being a loose one to afford play so that the restoring latch 48 may move toward and away from the face of the 95 driving plate.

The upper end of the restoring latch 48 is provided with an inclined lip 51.

A flat or leaf spring 52 (Fig. 10) has one 100 end secured to the driving plate 43 by screws 53, (Fig. 1), the remainder of the spring being free for movement toward and away from the face of said driving plate; the extremity of the spring bears on the driving pin 46 with a constant pressure. 105 The spring 52 tends to force the driving pin 46 toward the worm wheel 42 for the purpose of snapping said pin into one of the holes 44. Normally this action of spring 52 is resisted so that the pin is held 110 in retracted position, as shown in Fig. 2.

The operating lever 16 which is shown in detail in Figs. 8 and 9 is connected by rivets 54 passing through holes therein, to a piece 55 which, in turn, is pivoted to the casing 115 18 at 17.

The forward end of the operating lever, as shown in Figs. 2, 8, 9, is bent at an angle of about thirty degrees as shown at 57 to correspond to, and co-operate with, the substantially similarly angled part 51 on the upper end of the restoring latch 48 (Figs. 2, 4, 5). The object of providing these angled parts is to provide for a camming action to occur by which the restoring latch 120 is released when the starting bar 5 is depressed, to thus permit the spring 52 to project the driving pin 46 into one of the holes 44 and, also, to automatically retract the driving pin 46 when the driving plate 125 130

43 has made one complete revolution, assuming that the starting bar 5 has been released. If, however, the starting bar 5 is held in this depressed position, there will be 5 no interference with the part 51 of the restoring latch 48 and, consequently, the driving pin 46 will remain in the hole 44, thus maintaining the clutched relationship of the driving plate 43 and the worm gear 42. 10 So long as the starting bar 5 is held depressed, the drive mechanism will repeatedly operate the driving piece 3 of the calculating machine.

A stop or abutment pin 58, Fig. 1, which 15 projects from the driving plate 43 receives whatever strain is applied to the restoring latch 48 and relieves whatever strain would be transferred to the driving pin 46 when the angled part 51 on the restoring latch 20 48 engages the angled part 57 on the operating lever 16.

The means employed for transmitting motion from the driving plate 43 to the piece 3 of the calculating machine comprises links 25 4, Figs. 1 and 2, which are adjustably connected together by a bolt 59 and nut 60, the shank of the bolt passing through an elongated slot in the ends of said links. The 30 links are provided with engaging corrugations or teeth to avoid any possibility of relative slippage. The links carry hubs 61 which are provided with hardened rollers 62. The lowermost link is connected to the extended end of driving stud 50 and is held 35 by a screw 63. The uppermost link is connected to a stud 64 held by nut 65 to the driving piece 3. Thus, wide, anti-friction connections are provided between the links 4 the parts 43 and 3.

40 Pivoted to the casing by a screw 66 is back stop pawl 67, Figs. 1, 11, 12, 13, which is provided with an upwardly extending cam-shaped projection 68 which is adapted to engage a cam roller 69 carried by the 45 stud 50, Fig. 2. At its left hand end, the pawl 67 extends at right angles to its length, as shown in Figs. 11 and 12, and is there seated on a compression spring 70, Fig. 1, said spring being located in a barrel 71 and 50 capable of adjustment, to regulate its tension, by an adjusting screw 72 which has a lock nut 73. By this means the back stop pawl 67 is made to resist forward movement when struck by a roller 69 on the turning 55 of the driving plate 43 in a counter-clockwise direction. The slot or notch appearing in Fig. 13 receives a guiding device, 74, to prevent lateral springing of the back stop pawl 67.

60 The purpose of the back stop pawl 67 is to eliminate swinging or oscillating movement of the driving plate 43. Assuming that the starting bar 5 has been depressed and the driving pin 46 has entered one of 65 the holes 44, the counter-clockwise rotation

of the driving plate causes the roller 69 to strike the cam projection 68 on the back stop pawl 67 which thus affords a buffer action due to the employment of spring 70 so that when the part 70 51 of the restoring latch 48 engages the part 57 of the operating lever 16 to retract the pin 46 from hole 44, the rotation of the driving plate is arrested by the back stop pawl 67. As soon as the roller 69 passes the peak of the cam 68, the latter moves upwardly and exerts a wedging action on said roller (as viewed in Figs. 1 and 12) as the right hand edge of the projection 68 is slightly tapered or inclined. 80

A removable cover 75 is attached to the face of the casing 18 by screws 76, Fig. 2, entering corresponding screw threaded holes seen in Fig. 1. The cover 75 carries an electric switch 77. Wires from the motor 20 to the switch enter the cover 75 through holes 78, such wires being omitted from the drawings for the sake of clearness.

By locating the switch on the cover 75, it is conveniently arranged for operation 90 and, when the cover is removed, immediate access may be had to the operating mechanism.

When the switch 77 is turned to the "on" 95 position the motor 20 is energized and the armature shaft 23 driven and the worm 27 is revolved due to the frictional manner in which the worm is coupled to the shaft. The worm gear 42 is revolved by worm 27.

The angular part or cam 51 of the restoring latch 48 being engaged by the angular part 57 of the restoring latch operating lever 16, the driving pin 46 remains disengaged from the worm gear 42 as shown 100 in Fig. 2.

When the starting bar 5 is depressed, through the intermediate mechanism, the lever 16 is swung on its pivot 17 which results in the cam end 57 lifting clear of the cam end 51 of the restoring latch 48. Immediately this occurs, the driving pin 46 is snapped by spring 52 into the next hole 44 which comes opposite said pin during the counter-clockwise revolution of the worm wheel 42. A number of holes 44 are 110 provided so that there will be a quick engagement of the pin 46 immediately after said pin is released.

Once the pin 46 enters one of the holes 44, the driving plate 43 is turned as a unit with the worm wheel 42 and, through the links 4, the driving piece 3 of the calculating machine is operated, thus putting the calculating machine through its cycle of operations. 120

Should the starting bar 5 be quickly released, as is usual in most operations of a calculating machine, the lever 16 will resume its normal position before the driving plate 43 has made a complete revolution and thus the cam part 57 will be positioned 125 130

so that it will be struck by the cam part 51 on the restoring latch 48 when the revolution has been completed.

- Prior to the engagement of the cam parts 57 and 51, however, the roller 69 which is mounted on the stud 50, engages the beveled projection 68 of the back stop pawl 67. The back stop pawl, due to the action of spring 70, serves as a bumper or buffer to check the rotation of the driving plate and just before the cam parts 57, 51 engage, the roller 69 passes off of the peak of the part 68, whereupon the back stop pawl rises and its edge wedges against the said roller. Consequently, when the parts 57, 51 engage for the purpose of retracting the driving pin 46 from the hole 44, the arrest of the driving plate 43 is instantaneous and there is no "lash" or swinging motion of the driving plate. The engagement of the cam surfaces 57, 51 results in instant disengagement of the pin 46 from the hole 44.

The provision of the friction drive for the worm 27 serves as a safety device when the pin 46 is projected into a hole 44, or withdrawn therefrom, thus relieving the mechanism from strain at these times.

The friction drive for the worm 27 also serves the important purpose of acting as a safety device should the mechanism of the calculating machine "stall" or become blocked for any cause as the armature shaft would then revolve inside the worm and no undue strain be put upon any of the parts of the mechanism, affording the operator ample opportunity to turn the switch 77 to shut off the current and stop the motor.

I claim:

1. In an electric drive for calculating machines, the combination with a driving wheel provided with engageable means, of a rotarily mounted member, a clutching device carried by said member and adapted for engaging said engageable means of the driving wheel, a movably mounted restoring device carried by the rotarily mounted member adapted for retracting the clutching device to disengage it from the driving wheel, an abutment on the rotarily mounted member which takes up strain to which the restoring device is subject, an operating device adapted for manipulation which controls the operation of the restoring device, and means cooperating with the rotarily mounted member to check it and prevent it from having "lash" or overthrow after it has turned a predetermined distance.

2. In an electric drive for calculating machines, the combination with a driving wheel having a hole, of a rotarily mounted member, a spring-pressed slidable driving pin carried by said rotarily mounted member and adapted, when free, to enter said hole, a movably mounted restoring device carried by the rotarily mounted member which is

adapted to retract and retain, the pin free from the hole, an abutment on the rotarily mounted member which takes up strain to which the restoring device is subject and releasable controlling means adapted to cooperate with the restoring device to hold the pin in retracted position.

3. In an electric drive for calculating machines, the combination with a driving wheel provided with engageable means, of a rotarily mounted member, a clutching device carried by said member and adapted for engaging said engageable means of the driving wheel, a restoring device carried by the rotarily mounted member adapted for retracting the clutching device to disengage it from the driving wheel, a controlling device, adapted for manipulation, which embodies a cam adapted to cooperate with the restoring device for the purpose of disengaging the clutching device from the driving wheel, and an arresting device adapted to cooperate with the rotarily mounted member for the purpose of checking its rotation just prior to the engagement of the restoring device with the cam means aforesaid.

4. In an electric drive for calculating machines, the combination with a frame, of rotarily mounted driving and driven elements, means for clutching and de-clutching said elements, means independent of the driven element for controlling the clutching and de-clutching means, and a separate arresting device movably mounted on the aforesaid frame adapted to cooperate with the driven element for the purpose of automatically checking its rotation and preventing back-kick or swinging movement thereof after the driven element has completed its predetermined cycle of rotation.

5. In an electric drive for calculating machines, the combination with a frame, of rotarily mounted driving and driven elements, normally-restrained and automatically-acting means adapted for clutching said elements when released, controlling means for said clutching means which normally restrains the said means and is also adapted to automatically throw-out said clutching means after the driven element has completed its predetermined cycle of rotation, and a separate arresting device movably mounted on the aforesaid frame which is adapted to cooperate with the driven element for the purpose of automatically checking its rotation and preventing back-kick or swinging movement after said driven element has completed its aforesaid cycle.

6. In an electric drive for calculating machines, the combination with a driving wheel having engageable means, of a rotarily mounted plate normally free of the driving wheel, a movably mounted clutching device carried by the rotarily mounted plate which is adapted, when free, to engage the engage-

6

able means of the driving wheel, a movable restoring latch carried by the rotarily mounted plate and cooperating with the clutching device aforesaid, spring means for 5 actuating the clutching device when the latter is free to cause said clutching device to engage the engageable means of the driving wheel, a controlling device having a cam engageable with the restoring latch when 10 the rotarily mounted plate is in a predetermined position to release the clutching device from the driving wheel and against the action of the spring means aforesaid, and a movable, spring actuated, back stop pawl 15 adapted to check or arrest the rotation of the plate aforesaid just prior to the engagement of the restoring latch with the cam of the controlling device.

7. In an electric drive for calculating 20 machines, the combination with a driving wheel having engageable means, of a rotarily mounted plate, a driving pin slidably carried by the plate and adapted, when free, to engage the engageable means of the driving 25 wheel, a movably mounted restoring latch carried by, and rotatable with, the plate and engaged with said pin, said latch having a cam, an abutment on the rotarily mounted plate which takes up strain to 30 which the restoring latch is subject, a spring

carried by the plate which engages the pin and is adapted to cause said pin to engage the engageable means of the wheel when said pin is free, and an operating lever provided with a cam which is normally positioned for engagement by the cam of the restoring latch but which may be manipulated to disengage its cam from the cam of the latch to permit the pin to clutch the driving wheel.

8. In an electric drive for calculating machines, the combination with a driving wheel and a rotarily mounted member having means by which it may be clutched to, or de-clutched from, the driving wheel, of 40 means controlling the clutching and de-clutching action aforesaid, a spring actuated back stop pawl having a cam surface and a shoulder, and a device on the rotarily mounted member adapted to ride on the cam of said pawl and then to be engaged by said shoulder when the parts are assuming de-clutching position, said pawl thus serving to check the rotation of the rotarily mounted member and to prevent it 45 from swinging when de-clutching has been effected.

50 In testimony whereof I affix my signature.

FREDERICK W. BERNAU.
